Patented Oct. 1, 1918.

UNITED STATES PATENT OFFICE.

ALFRED L. EUSTICE, OF CHICAGO, ILLINOIS, ASSIGNOR TO ECONOMY FUSE & MANUFACTURING COMPANY, OF NEW YORK, N. Y., A CORPORATION OF NEW YORK.

FUSE-CLIP ATTACHMENT.

1,280,431.

Specification of Letters Patent.

Patented Oct. 1, 1918.

Application filed September 9, 1914. Serial No. 860,823.

To all whom it may concern:

Be it known that I, ALFRED L. EUSTICE, a citizen of the United States, residing at Chicago, in the county of Cook and State 5 of Illinois, have invented certain new and useful Improvements in Fuse-Clip Attachments, of which the following is a specification.

My invention relates to fuse clip attachments, and is particularly adapted for use in connection with clips of readily electrically-conducting material, such as copper, which are designed to receive the terminals of cartridge fuses of the ferrule or knife-blade 15 type.

On account of the fact that fuse clips are practically exclusively constructed of copper, it is a frequent occurrence that these clips become bent so that on insertion of a 20 cartridge fuse the contact between the terminals of the fuse and the fuse clips is unsatisfactory. Moreover, even under the best conditions by the present practice the contact depends on the resiliency of the metal 25 of the clips, and no positive means are used to insure a tight contact. This often results in the failure of contact between the complete contact surfaces of the terminals and the clips.

It has been proposed to reinforce the resiliency of the members of a fuse clip by applying thereto an auxiliary spring clip having flat bearing arms similar to the arms of the clip. But while this may suffice to 35 increase the pressure between the clip arms and the blade of the fuse so long as the clip arms retain their normal shape, it is of little benefit when the clip arms become distorted, for the reason that the auxiliary clip covers 40 so much of the area of the clip arms as to interfere with the action of pressing the clip arms back into shape upon the fuse blade; moreover, the use of a spring for this purpose is wholly inadequate.

It is the object of my invention to overcome the above-mentioned difficulties by providing a clip attachment which is quickly and readily applicable to the fuse clips and which bears upon the clip arms by what may 50 be termed "spot contact", and is shiftable to different positions thereon so that by localizing the point of pressure and developing the excessive pressure obtainable from mechanical means, such as a wedging screw, the por-

tions of the clip arms which tend to set open 55 may be directly encountered and pressed upon the blade, and thereby insure a good contact between the fuse terminals and these clips.

The various advantages of my invention 60 will be more readily understood by reference to the accompanying drawings, which show a preferred embodiment of my invention, and in which:

Figure 1 is a plan of a section of a panel 65 containing several cartridge fuses inserted in clips which are provided with the clip attachments constituting my invention;

Fig. 2 is an end elevation of one of the cartridge fuses, its clip, and the clip attachment shown in Fig. 1; and

Fig. 3 is a fragmentary side elevation of the parts shown in Fig. 2.

The panel 10 has attached thereto, by means of the screws 11, or otherwise, a plurality of fuse clips 12 which are adapted to receive the knife-blade terminals 13 of the cartridge fuses 14. The clips 12 are usually constructed of copper or other readily electrically-conducting material, and are provided with arms 15 which at their outer edges are bent to form the lips 16.

The arms 15 of the clips 12 are very apt to become bent or otherwise fail to provide a satisfactory contact with the terminals 13 85 of the safety fuses. To provide such a satisfactory contact I use the fuse clip attachment 17, which consists of a pair of spring arms 18 having reduced ends proportioned for "spot contact" with the arms of the clip 90 as distinguished from contact therewith through an extended area, suitably bent at their inner ends to engage the sides of the clip arms 15 just inside of the lips 16 or elsewhere upon the sides of the clip which 95 the bifurcation of the attachment permits. The arms 18 are joined at the outer end of the clip attachment, and this outer end is threaded, the threads extending for some distance along the arms 18, as clearly indicated in Figs. 2 and 3. Each of the clip attachments 17 is provided with a wing nut 19, which is inserted over the outer end of the clip attachment and has threaded engagement therewith. When the nut 19 is 100 in position near the outer end of the clip attachment, the arms 18 are separated from each other sufficiently by reason of their

spring character so that the inner ends of these arms may readily be slipped over the lips 16 of the fuse clip 12, or the clip attachment may be placed in position by slipping it over the end of the fuse clip. The wing nut 19 is then rotated so that the arms 18 are moved toward each other and brought into tight engagement with the arms 15 of the fuse clip. This serves to effect a good contact between the arms 15 of the fuse clip and the terminal 13 of the cartridge fuse. In order to remove the clip attachment it is only necessary to loosen the wing nut 19 and either slip the clip attachment from the fuse clip by moving it along the latter until the clip attachment becomes disengaged from the end of the fuse clip, or by allowing the arms 18 to become open sufficiently so that the clip attachment may be removed directly over the lips 16.

I have described my fuse attachment as used in connection with fuse clips for cartridge fuses of the knife-blade type, but it will be understood that it could be used with equal facility in connection with clips for ferrule type fuses.

It will be apparent to those skilled in the art that many changes could be made in the detailed construction of the clip attachment

which I have described without departing from the spirit or scope of my invention.

What I claim is:

1. The combination of a pair of fuse clip arms and a clamp spanning the clip arms and having contact parts engaging said arms and being of less area than the arms, said clamp being movable upon the clip arms to shift the points of engagement between said contact parts and the clip arms and also provided with means to regulate the pressure of the contact parts with the clip arms.

2. The combination of a pair of fuse clip arms and a substantially U-shaped clamp spanning the clip arms, the extremities of the legs of the clamp being of less area than the clip arms and engaging said arms; said clamp being movable upon the clip arms to shift the engagement thereof with said clip arms, and means upon the clamp to regulate the pressure of the legs upon the clip arms.

In witness whereof I hereunto subscribe my name this 4th day of September, A. D. 1914.

ALFRED L. EUSTICE.
